UNITED STATES PATENT OFFICE.

AARON CHARNEY, OF LYNN, MASSACHUSETTS.

GLOVE.

1,069,110.

Specification of Letters Patent. Patented Aug. 5, 1913.

Application filed May 4, 1912. Serial No. 695,048.

To all whom it may concern:

Be it known that I, AARON CHARNEY, a citizen of the United States, residing at Lynn, in the county of Essex and State of Massachusetts, have invented new and useful Improvements in Gloves, of which the following is a specification.

My invention is a glove, formed from two blanks of novel design, and stitched into final form by two continuous seams.

In the drawings: Figure 1 shows the main blank and indicates the first step in stitching; Fig. 2 shows the small blank; Fig. 3 shows the second step in the stitching; Fig. 4, a further step; and Fig. 5, a completed glove.

My invention is particularly adapted to the making of working gloves of drill or duck, such as are used by working men, as chauffeurs, machinists, motor-men, and the like, for the purpose of protecting their hands from dirt and abrasion, in performing their duties. In such gloves the first consideration is one of cheapness of production, in order that the gloves may be sold at a price which will permit of frequent replacement, as the gloves become soiled or worn in use. In gloves as ordinarily made, the glove is made up of the palm piece, having four projecting finger parts to form the inner side of the fingers; a back piece, having four projecting finger parts to form the outer or back side of the fingers; a thumb blank, and, usually, six gusset blanks 30 to be set in on the sides of the fingers to give the requisite circumference to the fingers.

In my new glove, the main portion of glove, including the thumb, is formed of one integral sheet, so designed that there is little waste of material in cutting the blank, as will be obvious from an examination of Fig. 1. The blank, as shown in Fig. 1, will produce either a right hand or a left hand glove, according as it is folded.

In the drawings, A is the main or body blank of the glove, B is the small blank. The blank shown in Fig. 1 is supposed to show what will ultimately be the outside of the glove which is indicated by *o*, while the parts of the material, which will ultimately be inside of the glove are marked *x*. The blank is divided by lines *a*, *a'*, *a''*, which indicate the lines of folding of the glove preparatory to stitching. Part 1 is the palm portion having integral projections 11, 12,

13 and 14, to form the inner or palm side of the fingers of the completed glove. Part 2 is the back portion integral with part 1 and having integral projections 21, and 24, 60 to form the back or outer parts of the first and little fingers of the completed glove. Part 3 forms part of the wrist portion and, coöperating with part 15 forms the thumb.

B is the small blank, formed in two sections *b*² and *b*³, which sections form the backs and sides of the second and third fingers as will be obvious from a consideration of Figs. 1 and 5 of the drawings, these sections *b*² and *b*³ extending in the same 70 general direction side by side, and back of the fork of the fingers lies an integral extension which, as will be hereinafter described, is attached by sewing to the blank *a* and gives the necessary fullness for the 75 back of the glove, all as clearly shown in Figs. 1 and 5.

The glove is assembled and stitched, as follows: The blank is laid out as in Fig. 1 with the outside, *o*, of the glove uppermost. 80 The blank B is first stitched to blank A, the *x* side being uppermost at the commencement of the operation. The attaching seam is begun at point *p* (Figs. 1 and 2), passing to a turning point at *p'*. Blank B is turned 85 on the sewing machine needle, as on a pivot at this point, the flexible material of the glove permitting this and the seam continued to *p*², where another turn is made and the seam continued to *p*³. The blank B 90 by this operation has been reversed and when the united blanks are pulled straight, will be found to have its *o* side uppermost, in conformity to the other blank. The blank A is now folded along line *a*², and 95 again on line *a'*, then folded to bring the palm 1 and back 2 portions in opposition, and the curved edge of part 3 into position with the curved wrist portion of part 1. The second seam is then begun at the wrist, 100 stitching the edges of part 3 and 1 together (see Fig. 3) then following by stitching part 3 to the opposing edge of part 15 until the fold *a*² is reached, then along the outer side of the first finger portion, connecting 105 the inner portion 11 of that finger with the back portion 21. At the upper inner end of the first finger the edge of part *b*² of blank B is reached and stitched all around to part 12 of the palm piece, following along by 110 stitching part *b*³, to part 13 of the palm piece, then along the inside of the little

finger, stitching parts 14 and 24 together, around the tip of the finger to fold *a*, thus completing the glove of two pieces with two seams. The glove is now turned right side out bringing the edges of the seams inside the finished glove.

The glove made as above described, requires less material than ordinary gloves, owing to the saving in seams; it is stronger, 10 since it is more nearly unitary in structure and has fewer seams to rip; it is more slightly and better fitting owing to the fact that the finger portions are not filled with seams. It is cheaper to cut, as two dies and 15 two cuttings only are required and it is cheaper to assemble and finish owing to the few parts and the fact that only two sewings or seamings are necessary.

I claim:

20 The two-piece glove above described,

made up of a blank having a palm portion carrying the inner part of the four fingers and the thumb; a back portion carrying the outer part of the first and little fingers and another portion to cover the outside of the 25 thumb and wrist; a second blank shaped to form the backs and sides of the second and third fingers, the respective finger pieces lying side by side and having an extension back of the fork of the finger pieces to 30 reach and cover the fork of the fingers from back to palm and secured to the back portion of the first blank between the projections for the first and fourth fingers.

Signed by me at Boston, Massachusetts, 35 this 30th day of April, 1912.

AARON CHARNEY.
